UNITED STATES PATENT OFFICE

OSCAR A. OESTERLE, OF HENRYETTA, OKLAHOMA

ORE SINTERING CAR

Application filed June 12, 1930. Serial No. 460,707.

This invention relates to improvements in sintering machines, more particularly to an improved car structure for the carrying out of a sintering process.

5 The primary object of the present invention is to provide a sintering car for metalliferous sulphur bearing ore for the intermittent burning of such ores and so designed as to produce an even forced draft through 10 the ore after the same has been fired so that the reduction of the ore will take place evenly and thoroughly.

Other objects and advantages of the present invention will become apparent as the 15 description of the same proceeds and the invention will be best understood from a consideration of the following detailed description taken in connection with the accompanying drawings forming part of this specification, with the understanding, however, that the invention is not confined to any strict conformity with the showing of the drawings but may be changed or modified 20 so long as such changes or modifications mark no material departure from the salient features of the invention as expressed in the 25 appended claims.

In the drawings:

Figure 1 is a view partly in side elevation 30 and partly in longitudinal section of the sinter car embodying the present invention.

Figure 2 is a sectional view taken on the line 2—2 of Figure 1.

Figure 3 is a view partly in top plan and 35 partly in horizontal section of one end of the car structure.

Referring more particularly to the drawings wherein like numerals of reference indicate corresponding parts throughout the 40 several views, the numeral 1 indicates generally the body of the sintering car embodying the present invention. This car, as shown, comprises a base portion made up 45 of a pair of channel beams 2 which are mounted in any suitable manner upon the axles 3 of two or more pairs of flanged wheels, each of which is indicated by the numeral 4.

These wheels are mounted to rotate on suitable 50 bearings about the axles 3 which bear-

ings have not been shown as any suitable type may be employed for this purpose.

The frame beams 2 have connected thereto the upwardly and outwardly directed side wall sheets 5 which form the lower portion of the car body, these sheets being of steel of suitable weight. At each end of the car structure an end sheet 6 connects the end edges of the side sheets 5 and coacts with a bottom 7 to close the lower part of the car 55 structure which constitutes a draft chamber. 60

One end wall 6 of the car body is provided with a draft aperture 8 about which on the outer face of the end wall is a beveled flange 9.

Each of the side walls 5 terminates at its 65 upper portion in a vertically disposed section 10 and the inner face of each of these vertical sections has secured thereto a cast metal liner 11. Each of the end walls also has secured to its inner face and adjacent 70 the top thereof a liner 12 similar to the liners 11, the lower edges of the liners 12 being in the same plane as the lower edges of the liners 11.

Each of the liners 11 upon the side walls 75 of the car body is provided with an inwardly projecting longitudinal rib 13 and above this rib there are formed at spaced intervals vertical slots 14. The slots 14 receive the ends of the transverse grate bars 15 which rest 80 upon the flanges 13 in the manner shown. Each of these grate bars has fixed transversely of the top edge thereof a number of plates 16 the ends of which come into abutting relation with the plates upon the adjacent bars. 85

Disposed beneath the grate bars 15 and in relatively close relation thereto is a transverse horizontal plate 17 which is provided throughout with apertures 18.

Spaced from and disposed beneath the apertured plate 17 is a second plate 19 which, like the plate 17, extends the full length and width of the car body, the edges of this plate being turned to provide the flanges 20 which are bolted or otherwise secured to the inclined portions of the side walls 5. This plate 17 is provided with short transversely extending slots 21 and in addition is upwardly curved or cambered as is clearly shown 90 in Figure 2.

In operation the ore to be treated, together with the necessary combustible material mixed therewith, is placed in the top of the car upon the plates 16 of the grate bars. The 5 car is then shifted along the tracks 22 upon which it is mounted, to bring the flange 9 of the draft opening into the end of a suitably positioned fixed suction tube 23. After the car has been coupled with the suction tube 10 the charge of ore is ignited, any suitable means being employed for this purpose as for example the usual flame igniter, not shown, and after the burning of the ore is started it is maintained through the draft 15 of air drawn therethrough by the suction means connected with the suction pipe 23. By employing the perforated plate 17 the draft through the charge is equalized and this is further improved by the use of the 20 slotted plate 19. The suction is thus made uniform over the entire grate bar surface and results in the production of a uniformly sintered product, the fumes from which are of sufficient sulphur dioxide concentration to be 25 used for the manufacture of sulphuric acid.

Having thus described my invention, what I claim is:

1. An ore sintering car, comprising a body having bottom, side and end walls, means for 30 coupling a suction tube with one wall for the removal of air from the interior of the car, a grate disposed in the upper part of the car adapted to have ore ignited thereon, and an apertured plate partitioning the upper part 35 of the body between the grate and said means for equalizing the air draft therethrough and the producing of uniform combustion of the ore.
2. A sintering car, comprising a wheel supported body having bottom, side and end walls, one of said walls having an aperture therethrough, means surrounding said aperture for facilitating the coupling of a suction pipe with the wall, a lining disposed 45 about the inner surface of the side and end walls at the upper portion of the car, a grate structure within the upper portion of the car in the area between the lined walls, and a perforated draft equalizing plate disposed 50 within the body beneath said grate structure, said grate structure being designed to support burning ore.
3. An ore sintering car, comprising a body having bottom, side and end walls, one of 55 said end walls having an aperture therethrough, a flange upon the apertured wall surrounding said aperture and designed to facilitate the coupling of a suction draft tube thereto, liners secured against the inner faces 60 of the side and end wall at the tops thereof, the liners carried by the side walls being recessed, grate bars extending transversely of the body and having their ends disposed in said recesses, and superposed plates within 65 the body beneath the grate bars designed to

equalize the draft through said grate, each of said plates being apertured, the apertures of one plate being in the form of short transversely extending slots.

4. An ore sintering car, comprising a body 70 having bottom, side and end walls, one of said end walls having an aperture therethrough, a flange upon the apertured wall surrounding said aperture and designed to facilitate the coupling of a suction draft tube 75 thereto, liners secured against the inner faces of the side and end walls at the tops thereof, the liners carried by the side walls being recessed, grate bars extending transversely of the body and having their ends disposed in 80 said recesses, superposed plates within the body beneath the grate bars designed to equalize the draft through said grate, each of said plates being apertured, the apertures of one plate being in the form of short transversely extending slots, and a plurality of short transversely extending plates disposed on edge upon each grate bar, the plates on 85 one grate bar being in edge abutting relation with the plates on the adjacent grate 90 bars.

5. An ore sintering car, comprising a wheel 95 supporting body having bottom, side and end walls, said side walls being upwardly diverging through a portion of their height and terminating in vertical portions, a liner overlying the inner surface of the vertical portion of each side wall and the upper portion of the adjacent inner face of each end wall, each of said side wall liners having a longitudinally extending flange and a plurality of recesses therein above the flange, transversely extending grate bars having their ends resting upon said flanges and engaging in said 100 recesses, a horizontal apertured plate disposed beneath said grate bars, a cambered plate disposed beneath said horizontal plate and having short transverse slots formed therethrough, one of said end walls having an opening therethrough, and a flange surrounding said opening for facilitating the 105 coupling of a stationary draft suction pipe thereto.

6. An ore sintering car, comprising a body 110 having bottom, side and end walls, one of said end walls having a draft aperture therethrough, grate bars extending transversely of the body between said side walls, and superposed spaced plates within the body beneath the grate bars designed to equalize the draft 115 through the grate, each of said plates being apertured, the apertures of one plate being in the form of short transversely extending slots.

7. An ore sintering car, comprising a body 120 having bottom, side and end walls, one of said end walls having a draft aperture therethrough, grate bars extending transversely of the body between said side walls, an apertured plate partitioning the upper part of 125

the body beneath the grate bars and designed to equalize the draft through the grate, and a plurality of short plates disposed on edge upon and transversely of each grate bar.

8. An ore sintering car, comprising a wheel supported body having bottom, side and end walls, said side walls being upwardly diverging through a portion of their height and terminating in vertical portions, a liner overlying the inner surface of the vertical portion of each side wall and the upper portion of the adjacent inner face of each end wall, transversely extending grate bars having their ends secured in the liners of the side walls, a horizontally disposed apertured plate beneath said grate bars, and a cambered plate disposed beneath said horizontal plate and having short transverse slots formed therethrough, one of said end walls having a draft opening therethrough at a point beneath the cambered plate.

In testimony whereof I hereunto affix my signature.

OSCAR A. OESTERLE.
